CLAIM

The ornamental design for a front panel for a motor vehicular combined radio and cassette player, or the like, substantially as shown and described.

DESCRIPTION

FIG. 1 is a front perspective view of a front panel for a motor vehicular combined radio and cassette player, or the like showing our new design, with the broken line environment included for illustrative purposes;

FIG. 2 is a top plan view;

FIG. 3 is a front elevational view;

FIG. 4 is a bottom plan view;

FIG. 5 is a left side elevational view; and

FIG. 6 is a right side elevational view.
